(57) **CLAIM**

The ornamental design for a package with base closure, top closure, side panel edge and kite shaped edge, as shown and described.

DESCRIPTION

FIG. 1 is a top plan view of a package with base closure, top closure, side panel edge and kite shaped edge showing our new design in a flattened blank configuration;

FIG. 2 is a bottom plan view of the flattened package of FIG. 1;

FIG. 3 is a partially-folded top plan view of the package of FIG. 1, showing the two middle panels, with the two side panels and far right fold tab of the package folded underneath;

FIG. 4 is a bottom plan view of the partially-folded package of FIG. 3, showing the two side panels including the far right fold tab of FIG. 1;

FIG. 5 is a left side elevational view of the package of FIG. 1 in an assembled configuration;

FIG. 6 is a front elevational view of the package of FIG. 1 in an assembled configuration;

FIG. 7 is a right side elevational view of the package of FIG. 1 in an assembled configuration;

FIG. 8 is a back elevational view of the package of FIG. 1 in an assembled configuration;

FIG. 9 is a top plan view of the package of FIG. 1 in an assembled configuration;

FIG. 10 is a bottom plan view of the package of FIG. 1 in an assembled configuration; and,

FIG. 11 is a perspective view showing the front, top and left sides of the package of FIG. 1 in an assembled configuration. The broken lines showing the package with base closure, top closure, side panel edge and kite shaped edge are included for the purpose of illustrating environmental structure and form no part of the claimed design. The claim is limited to the solid lines in the drawings.
